(57) **CLAIM**

The ornamental design for a recessed lighting fixture, as shown and described.

DESCRIPTION

FIG. 1 is a perspective view of a recessed lighting fixture showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is an enlarged cross-sectional view taken along line 8—8 in FIG. 6, with the internal parts omitted for ease of illustration.

The broken lines showing portions of the omitted internal structure of the recessed lighting fixture in FIG. 8 form no part of the claimed design.
